Nos. 1751

Ernest Kaufmann, of Philadelphia, Pa.
Letters Patent No. 1751. Dated. Apr. 28. 1863.

The Schedule referred to in these Letters Patent of making part of the same.

To all whom it may concern:

Be it known that I, Ernest Kaufmann, of the City, and County of Philadelphia, in the State of Pennsylvania have invented a certain new ornamental design for Ice Pitchers; and I do hereby declare that the same is clearly represented in the accompanying drawing (making part of this specification) in which -

A. is the main body of the pitcher.

B. is the cover, hinged at B. and surmounted by a knot C, formed to represent a Malone partly immersed in water and resting upon cakes of floating ice.

D. is the spout, the exterior of which represents the head of an eagle, and is surrounded with leaves and flowers.

E. is the handle of the pitcher, constructed with a thumb knob e. which is formed to represent the head of a griffin.

F. represents a band of scroll work, extending around the top of the pitcher from the handle to the spout.

What I claim as new, and desire to secure by Letters Patent, is the design for an Ice Pitcher, herein represented and described.

Witnesses.
